STUFFED TOY ANIMAL FIGURE

Barbara H. Gorman, Mansfield, Conn. (Willington Oaks, Apt. 101, Daleville Road, Storrs, Conn. 06268)

Filed Nov. 5, 1973, Ser. No. 412,552

Term of patent 14 years

Int. Cl. D21—01

U.S. CL. D34—2 R

FIG. 1

FIG. 2

FIG. 3

FIG. 4

FIG. 5

FIG. 1 is an elevational view of a stuffed toy animal figure showing my design;

FIG. 2 is a rear view thereof;

FIG. 3 is a bottom view thereof;

FIG. 4 is a front view thereof; and

FIG. 5 is a top view thereof.

I claim:

The ornamental design for a stuffed toy animal figure, as shown and described.
